[57] CLAIM

The ornamental design for an angle measuring tool, as shown and described.

DESCRIPTION

FIG. 1 is a fragmentary top perspective view of an angle measuring tool in accordance with my new design;

1 Claim, 4 Drawing Sheets

FIG. 2 is a fragmentary top plan view thereof;

FIG. 3 is a fragmentary right side elevational view thereof, the left side being a mirror image;

FIG. 4 is a fragmentary bottom plan view thereof;

FIG. 5 is a front elevational view thereof;

FIG. 6 is a rear elevational view thereof;

FIG. 7 is a fragmentary top perspective view of an alternative embodiment of an angle measuring tool in accordance with my new design;

FIG. 8 is a fragmentary top plan view thereof;

FIG. 9 is a fragmentary right side elevational view thereof, the left side being a mirror image;

FIG. 10 is a fragmentary bottom plan view thereof;

FIG. 11 is a front elevational view thereof; and,

FIG. 12 is a rear elevational view thereof.

The fragmentary views of FIGS. 1-4 and 7-10 indicate that the angle measuring tool in accordance with my new design can be of any length.

FIG. 5

FIG. 6
